Primary Examiner — Mary Shannon Malley*Assistant Examiner* — Jennifer B Salazar(74) *Attorney, Agent, or Firm* — Birchwood IP(57) **CLAIM**

The ornamental design for a bark control device, as shown and described.

DESCRIPTION

FIG. 1 is a front, right and bottom perspective view of a bark control device, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area "9" in FIG. 1.

The equal-length broken lines in the drawings depict portions of the bark control device that form no part of the claimed design. The dash-dot-dash broken lines in FIGS. 1 and 9 depict the boundaries of the enlargements and form no part of the claimed design.
